US00D796497S

(12) **United States Design Patent** (10) **Patent No.:** **US D796,497 S**
(45) **Date of Patent:** ** *Sep. 5, 2017

(54) **CASE FOR ELECTRONIC DEVICE**

(71) Applicant: **Spigen Korea Co., LTD.**, Seoul (KR)

(72) Inventor: **Dae-Young Kim**, Seoul (KR)

(73) Assignee: **SPIGEN KOREA CO., LTD.**,
Geumcheon-Gu, Seoul (KR)

(*) Notice: This patent is subject to a terminal disclaimer.

(**) Term: **15 Years**

(21) Appl. No.: **29/573,088**

(22) Filed: **Aug. 2, 2016**

Related U.S. Application Data

(63) Continuation of application No. 29/495,236, filed on Jun. 27, 2014, now Pat. No. Des. 771,607.

(57) **CLAIM**

The ornamental design for a case for an electronic device, as shown and described.

DESCRIPTION

FIG. 1 is a front perspective view case for an electronic device showing my new design;

FIG. 2 is another front perspective view thereof;

FIG. 3 is a rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a front perspective exploded view of the case with the electronic device separately;

FIG. 11 is a rear perspective exploded view thereof;

FIG. 12 is a front perspective view of the case with the electronic device therein; and,

FIG. 13 is a rear perspective view thereof;

The broken lines depict unclaimed environment and form no part of the claimed design.

1 Claim, 13 Drawing Sheets
